(57) **CLAIM**

The ornamental design for a trim switch of control wheel for aircraft, as shown and described.

DESCRIPTION

FIG. 1 is a perspective view of a trim switch of control wheel for aircraft.

FIG. 2 is another perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof; and,

FIG. 9 is a referential view showing the use thereof.

The broken lines shown in FIG. 9 are for illustrative purpose only and form no part of the claimed design.

1 Claim, 9 Drawing Sheets
